UNITED STATES PATENT OFFICE.

ALEXANDER C. FRANKEL, OF NEWARK, NEW JERSEY, ASSIGNOR TO JACOB LAGOWITZ, OF SAME PLACE.

TRUNK-FASTENER.

SPECIFICATION forming part of Letters Patent No. 233,229, dated October 12, 1880.

Application filed April 15, 1880. (Model.)

To all whom it may concern:

Be it known that I, ALEXANDER C. FRANKEL, of Newark, in the county of Essex and State of New Jersey, have invented certain improvements in Trunk-Fastenings, of which the following is a specification.

My invention relates to a catch or fastening applicable to trunks, chests, &c., to hold them shut; and it consists in the peculiar construction and arrangement of parts, hereinafter described in detail.

Figure 1 represents a face view of my device in its locked position; Fig. 2, a central section of the same on the line *x x* of Fig. 1; Fig. 3, a similar section of the same as it appears when unlocked; Fig. 4, a section on the line *y y*.

A represents the body of the device consisting of a plate provided with holes to receive fastening-screws and with a front projection, *a*, which latter has its rear side made hollow to receive a spring, and notched at *b b* to receive the upper end of the catch or hasp.

B represents the hasp or catch, having at the upper end a cross-bar, *c*, seated in the notches *b* in the back of the body. From the ends of the cross-bar the hasp extends downward along both sides of the projection *a*, and terminates at the lower end in a tongue or end provided with a lip, *d*, and adapted to enter and engage firmly with the keeper-plate. The lip *d* has an upward inclination, in order that it may engage the more securely with the keeper and prevent the device from unlocking accidentally.

In order that the lip may be locked upward into the keeper, as stated, the recesses or grooves *b* in the body are made of such length as to permit a limited vertical play of the hasp, and in the back of the body beneath the upper cross-bar of the hasp there is mounted a spiral spring, *e*, which serves to urge the hasp upward. When the hasp is fastened the spring holds it upward and prevents the lip *d* from unlocking; but when it is desired to unfasten the device a slight downward pull or pressure will overcome the spring and depress the hasp, so that it may be disengaged and turned upward, as represented in Fig. 3. The pressure of the spring also causes sufficient friction to keep the hasp in its elevated posi-

sition when released and turned upward, as in Fig. 3. When the hasp is depressed a slight pressure is sufficient to cause the parts to lock.

In order to insure a smooth easy action of the parts a thin metal back plate, *g*, may be used behind the body, as shown.

The keeper-plate *C* is recessed, as shown, to receive the hasp, and in order that the latter may not be broken when the trunk is rolled or thrown about the keeper and the middle of the body are raised, as shown, to protect the hasp from blows.

In order to relieve the hasp and give the trunk additional security the body of the fastening is provided with two studs, *h*, which enter corresponding recesses in the keeper, as shown.

It will be noted that in my device the spring is not designed to and does not receive the strain, but that it serves merely to hold the hasp in its locked and unlocked positions, while the spring permits a very limited longitudinal movement of the hasp, in order that the latter may be unlocked and strain applied to open the lock will be resisted by the full strength of the hasp locking firmly and rigidly in place.

What I claim as my invention is—

1. The combination of the body-plate, the outwardly-swinging hasp connected securely to said plate, and having a slight longitudinal play thereon, the keeper, and the spring arranged to urge the hasp upward, as described and shown.

2. In a trunk-fastener, the combination of the body-plate, the outwardly-swinging and longitudinally-moving hasp, and the spiral spring arranged to urge the hasp upward endwise, and also to hold it in an elevated position when unlocked.

3. The combination of the body-plate, the spiral spring, the outwardly-swinging and longitudinally-moving hasp arranged to engage solidly with the body-plate and provided with the upwardly-inclined lip, and the keeper recessed to receive said lip.

ALEXANDER C. FRANKEL.
